CENTRIFUGE

Andrew F. Howe, St. Louis, Mo., assignor to Centrifugal & Mechanical Industries, Inc., St. Louis, Mo., a corporation of Missouri

Application January 10, 1946, Serial No. 640,209

4 Claims. (Cl. 233—2)

1

This invention pertains to centrifuges generally and concerns itself more particularly with centrifugal driers and clarifiers used in separating solids from fluids in which they are suspended or immersed.

In various industries it is often necessary to dry substances in large quantities and under conditions which make it infeasible to expel the moisture by heat or similar conventional methods. This is particularly true in the coal industry where washed coal is processed for use in refractory lined furnaces. Here it is necessary to dry the washed coal until its free moisture content is less than nine per cent, since water quantities greater than this will damage the refractories to the extent that the fuel cannot be used.

Because of the large quantities to be dried, the economics involved and other factors, such as continuous handling, centrifugal driers have been found particularly suitable for drying coal, and machines have been developed for this purpose.

Two problems have been presented in this particular process with the solution of which the instant invention deals. And while these problems may be introduced, by way of example, in their connection with coal drying, they are present in the same form in numerous other industries.

Thus, where the substance washed contains finely divided particles which are carried off in the washing fluid as waste in substantial amounts, it is desirable that this waste be reclaimed. Also, in some localities, it is necessary that the washing fluid itself be reused. With present equipment and methods neither of these desired results have been realized within economic limits making them feasible.

With the satisfactory solution of both of these problems as a desired result, it is a general object of the instant invention to provide a centrifugal separator which will remove substantially all of an immersed solid from its immersing fluid and simultaneously will remove substantially all of the immersing fluid from the solid matter processed.

It is also an object of the instant invention to provide a centrifugal separator by means of which solid matter may be removed continuously from an immersing fluid and separated into various categories of fineness.

Another object of the invention is to provide a centrifugal separator for detaching solid matter from a fluid continuously which will first separate the solids into various categories of fine-

2

ness and subsequently mix the separated solids into a composite mixture.

Still another object of the invention is to provide a centrifugal separator which will clarify an immersing fluid of solid matter to within less than one per cent by weight of the liquid.

Yet another object of the invention is to provide a centrifugal separator in which solids down to a predetermined minimum size are removed continuously from an immersing fluid by centrifugal screening and solids below said predetermined size are removed continuously from the fluid by solid bowl centrifuging.

It is a further object of the invention to provide a centrifugal separator having a solid bowl and a screen type centrifuge arranged coaxially and driven from a common source.

A further purpose of the invention is to provide a centrifugal separator having a centrifugal screen and a solid bowl arranged to be rotated about a common axis at a given speed and separate flights operative in conjunction with the screen and bowl also adapted to be rotated about said common axis and at a slower speed than said bowl and screen.

Further still, it is an object of the instant invention to provide a continuous centrifugal drier and clarifier having both a screen and solid bowl type centrifuge mounted coaxially and arranged to operate in series and having separate scrapers or wipers rotatively associated with both centrifuges arranged to operate at a speed differential and at a selected pitch whereby the degree of separation of a solid and its immersing fluid may be controlled.

Other objects and advantages will become apparent as the description proceeds and a more comprehensive understanding of the invention will be afforded from the following detailed specification when considered in conjunction with the accompanying drawings in which

Figs. 1 and 2 are vertical sectional views of a continuous centrifugal separator embodying the instant invention showing in elevation the left and right half sections thereof, respectively, as divided along a line A—A taken through the vertical axis of the machine.

Fig. 3 is an elevational view of a housing member incorporated in the machine showing its mountings, and

Fig. 4 is a partial sectional view of the machine taken along the lines 4—4 as indicated on Figs. 1 and 2.

With reference to Figs. 1 and 2 of the drawings, the invention contemplates a heavy frame

11 upon which all of the operative mechanisms are carried. This frame, which is substantially square, may be fabricated from structural steel members of desired sizes and weights. The machine is supported on four uprights, two of which are shown. These uprights 12 and 13 are fitted with base plates 14 and are connected by a pair of principal cross members 15 and 16. The two uprights not shown are connected by similar cross members and both of these assemblies are connected by four I-beams 17, 18, 19 and 21.

10 A motor mounting frame fabricated from three angle irons 22, 23 and 24 (Fig. 2) supports an electric motor 25 providing power for driving the machine's centrifugal separators.

15 A housing 26 (Fig. 3) is supported in the frame 11 in which a sleeve shaft 27 and a solid shaft 28 (Figs. 1 and 2) are journalled for rotation. This housing takes the form of a hollow truncated cone supported at its base on an annular ring 29 secured to the frame 11. The sloping sides 31 of the housing 26 are broken at 32 and extend into an offset 33 providing a mounting of a plurality of trucks 34 which are journalled for rotation about their individual axles fixed to the housing by the journals 35. These trucks are mounted at spaced intervals around the base of the housing and provide support for a scraping mechanism later to be described.

20 The center of the housing is occupied by a well 36, the walls 37 of which enclose two bearings 38 and 39 for the sleeve shaft 27. This particular shaft is directly driven by the motor 25, which mounts a pulley wheel 41 on its shaft 42. A complementary pulley wheel 43 is keyed to the sleeve shaft 27, and is driven by a compound V-belt carried over both pulleys.

25 The solid shaft 28 is driven at a different speed than that of the shaft 27 through a differential generally designated 44. This mechanism is contained in a suitable housing 45 in which a shaft 46 is journalled for rotation in two bearings 47 and 48. To the shaft 46, two gears 51 and 52 are keyed to rotate therewith. The first of these gears meshes with a gear 53 splined to the sleeve shaft 27 and the second with a hubbed gear 54 fixed to the solid shaft 28. This latter shaft terminates in a thrust bearing 55 and is supported in the sleeve shaft 27 by a bearing 56. A difference in the size of the gear 54 from that of the gear 52 provides the speed differential between the two shafts. Obviously they both rotate in the same direction.

30 Upon the upper end of the sleeve shaft 27 there is mounted a large wheel-like member, the hub 57 of which also takes the form of a hollow truncated cone. Radially projecting from the hub 57 are a plurality of spokes 58 which connect the same with a flanged rim 59. The base of a perforated conically shaped member 61, commonly referred to as a basket, rests in the flange of the rim 59 and within this basket is fitted a screen 62, which conforms substantially to the configuration of the basket. The top of the basket 61 is bearinged against the external surfaces of a feed spout 63 which rotates within an opening in the top of the basket. The arrangement of the basket and screen are more fully described in a patent to Andrew F. Howe, No. 2,321,207, filed August 25, 1941.

35 Also carried on the rim 59 and supported for rotation therewith is a solid bowl compartment 64 which is provided with a top 65 also bearing against the feed spout 63 in order that the latter may rotate in the former's central opening.

Near the outer edge of the top, a series of openings 66 are made which form a lip 67 around the wall of the solid bowl compartment at its top. In this instance, the solid bowl compartment is secured to the rim 59 by a number of brackets 68 placed at spaced intervals around the base of the bowl.

40 With the above described arrangement of the parts it will be noted that the solid bowl 64, the basket 61, and the screen 62 are rotated at the same speed by the rim 59 as driven by the sleeve shaft 27.

45 By similar means a flight 69 operating in connection with the bowl 64 and a flight 71 operating in conjunction with the screen 62 are driven at the same speeds by the solid shaft 28. Here the flight 71 is supported on a hub 72 by a series of spokes 73. The hub itself is keyed to the shaft 28 and is bearinged for rotation in the hub 57 by a bearing 74. The top of the flight 71 is bolted to the bottom of the spout 63 thereby providing a driving connection for rotating the spout.

50 The flight 69, on the other hand, is secured to the spout 63 by a plurality of pins 75 and is rotated therewith.

55 Each flight is made up of a series of scrapers which may range from straight members to helical members of two or more turns. In the illustrated embodiment the scrapers are shown in the form of helices and for the flight 69 are designated by the numerals 76, 77, 78, and 79. The flight 71 is made up with a group of scrapers 81, 82, 83, and 84. In each instance the respective scrapers carry the solids downwardly from the bowl and the screen and the degree of moisture separation therefrom is a function of the number of turns of the flights and the speed differential between the sleeve shaft 27 and the solid shaft 28.

60 Surrounding the solid bowl compartment 64 is a launder 85 into which the immersing fluid is discharged after the solid matter has been separated therefrom. This sluice or trough is fixed to the frame 11 and is provided with a removable cover 86. Located centrally in this cover is a funnel 87 into which the mixture of solid matter and its immersing fluid is continuously fed. This funnel discharges into the spout 63 from which the mixture is thrown by centrifugal force out through a series of openings 88 in the bottom thereof. A duct 85a carries the clarified fluid from the launder 85 to a point where it may be reused or discarded.

65 The solids from the bowl compartment are discharged through the spaces existing between the brackets 68 and from the screen 62 through the spokes 58, and are collected in a large circular cage 89, also fixed to the frame 11.

70 Initially, the solids from the screen 62 are thrown in an annular pile 91 at the outer extremities of the cage 89. As the pile is built up, these solids fall by gravity into the path of a plurality of rotating scrapers 92, which convey them to a discharge opening 93 in the bottom of the cage 89 from which point they may be continuously moved by any suitable means.

75 The solids from the bowl, on the other hand, may be collected if desired on a rotary conveyer 94 supported on the scrapers 92. From this conveyer these solids are plowed by a stationary plow 95 fixed to the frame 11 into a second discharge opening in the cage 89 formed by an inclined wall 96 thereof.

80 Both the scrapers 92 and the rotary conveyer 94 are driven at a relatively slow speed from

the same power source. Thus, the scrapers 92 are fixed at spaced intervals to a conically shaped apron 97, which is supported for rotation on a truck ring 98. This ring carries an outwardly extending flange 99 on the underside of which is a circular boss 101 which rides on the trucks 34, previously described.

A separate power source taking the form of an electric motor 102 (Fig. 1) is used to drive the ring 98. This motor, through a gear box 103 turns a shaft 104 on the end of which is keyed a spur gear 105 (Figs. 1 and 3). The teeth of this gear engage in and mesh with a circular band of teeth 106 forming a part of the ring 98 to rotate both the scrapers 92 and the rotary conveyer 94 fixed thereto.

The conveyer 94 is supported for rotation about the rim 59 on a series of brackets 107 formed from three angle irons 108, 109, and 111, each bracket being fixed to one of the scrapers 92.

Where it is desired to mix the fine solids discharged from the bowl 64 with those of coarser nature from the screen 62, the rotary conveyer 94 together with its supports 107 may be removed. In such case the fine solids will fall onto the apron 97 and will be mixed with the solids from the screen 62.

Operation

While the operation of the machine may be readily understood from the foregoing description, a complete cycle of operation will be summarized. First, the motors 25 and 102 are started and the machine brought up to operating speed. Then the mixture of the solids and immersing fluid, which is to be processed, is introduced into the machine continuously through the funnel 87. From the spout 63, into which the funnel empties, the mixture is thrown by centrifugal force out through the openings 88 in the bottom thereof against the screen 62 on the inside of the rotating basket 61. By centrifugal force, the liquid or immersing fluid, together with such of the solid matter as will pass the screen, is forced through the perforations of the screen and basket and into the solid bowl compartment 64.

In this first of the centrifuging operations about eighty-five to ninety-five per cent of the solids may be removed. These solids which do not pass the screen 62 are moved downwardly by the scrapers 81, 82, 83 and 84 of flight 71 which is rotating at a different speed from the screen 62. The time during which the solids are retained in the screen determines the degree to which they are freed of the immersing fluid, since they constantly become drier as they approach the bottom of the screen. Thus if the scrapers 81, 82, 83 and 84 are single turns, that is, if they circumscribe the flight 71 once in traversing its length, and if the speed differential between the screen and its flight is one revolution per minute, then each scraper will move its cargo of solids through the screen in a minute. The solids thus processed would be drier than would those processed by a half-turn flight which would carry them through in thirty seconds. Likewise if the speed differential were charged so that the flight would turn more rapidly relative to the screen the drying time would be decreased. The same is true of the flight 69 and the bowl 64.

Returning to the fluid which passes through the screen 62 and the basket 61, it strikes the inside surface of the flight 69 and is forced downwardly and out into the bowl compartment 64. This liq-

uid, containing a relatively small percentage of the extremely finely divided particles of the solid matter is centrifuged in the bowl 64 which revolves at the same speed as the screen 62. Here, however, the peripheral speed of the bowl is much higher due to its larger diameter, which condition gives to it a centrifugal action that causes the fine solids to be forced against the wall of the bowl where they are scraped downwardly by the flight 69.

The fluid thus freed from substantially all of its solid matter, is forced upwardly along the bowl until it is whipped out through the openings 66 in its cover 65. After it is expelled from the bowl it is collected in the launder 85 as a fluid substantially free of solid matter.

The solid matter is collected in a manner previously described in the cage 89. Its degree of dryness will have been determined by the flights selected and the speed differential.

In conclusion some of the features of the invention may be better understood by considering them in connection with a specific application. Thus in the drying of washed coal, and with properly selected flights and speeds, the fines may be separated out and processed for pulverized fuel, or other uses, or they may be mixed with the coarser coal. In the latter case, although the fines may contain as high as seventeen per cent moisture, the composite fuel will have much less than the critical nine per cent moisture content.

The economies involved may well be appreciated if coal containing six per cent of fines is processed in the machine at its maximum rated capacity of eighty tons per hour. In one run of twenty-four hours, some one hundred and fifteen tons of coal heretofore wasted would be reclaimed. Moreover, in communities where washing water is at a premium, the clarified water discharged from the launder of the machine could be used again, since it can be cleaned of solid matter to within one-half of one per cent. Water containing up to one per cent may be reused.

While a specific embodiment of the invention has been illustrated and described, it is apparent that the same may be practiced in other ways without departing from its basic concepts. Accordingly, the recitations and representations herein made are to be interpreted as illustrative only and not in a limiting sense, and, insofar as 50 the changes and embodiments to which the invention is susceptible fall within the scope of the appended claims they are included as if described.

What is claimed is:

1. In a centrifugal separator, a first and second vertically disposed shaft supported in a frame for coaxial rotation, said first shaft rotating within said second shaft, a basket supported on an end of said second shaft for rotation therewith, a conically shaped screen supported on said basket for rotation therewith and adapted to receive continuously a charge of fluid having separable matter contained therein, a solid bowl taking the form of an inverted truncated cone surrounding said screen and supported on said basket to rotate therewith, separate scrapers mounted for rotation on said first shaft and adapted to scrape the inside walls of said screen and said solid bowl, respectively, and means for rotating said first and second shafts at different rates of speed whereby said screen and said solid bowl are rotated at the same rate of speed and said scrapers are rotated at a common speed but different from the rate of rotation of the bowl and screen.
2. In a centrifugal separator, a solid bowl tak-

ing the form of an inverted truncated cone mounted for rotation about a vertical axis, a conically shaped screen mounted for rotation within said solid bowl about the latter's axis of rotation and adapted to be continuously charged with a fluid containing separable matter, said screen and said bowl being rotated at the same rate of speed, a first scraper comprising a solid conically shaped body and a plurality of scraper blades mounted thereon, said latter elements being adapted to scrape the inside walls of said screen, a second scraper comprising a solid conically shaped body adapted to extend in the form of a solid apron substantially over the external area of said screen but disposed at a distance therefrom and a plurality of scraper blades mounted on said second scraper adapted to scrape the internal walls of said solid bowl, and means for rotating said first and second scrapers at a common speed different from the common speed at which said screen and said solid bowl are rotated.

3. In a centrifugal separator, a solid bowl taking the form of an inverted truncated cone mounted for rotation about a vertical axis, a conically shaped screen mounted for rotation within said solid bowl about the latter's axis of rotation and adapted to be continuously charged with a fluid containing separable matter, said screen and said bowl being rotated at the same rate of speed, separate scrapers mounted to rotate at the same rate of speed but different from that of said screen and said bowl, said scrapers being operative to scrape the inside walls of said bowl and said screen whereby the said separable matter is discharged at the bottom of said bowl and said screen, and first and second collectors, each rotatable about an axis common to the axis of rotation of said bowl and said screen for separately collecting the separable matter discharged from said bowl and from said screen.

4. In a centrifugal separator, a solid bowl taking the form of an inverted truncated cone mounted for rotation about a vertical axis, a conically shaped screen mounted for rotation within said bowl about the latter's axis of rotation, a tubular spout arranged concentrically

with said axis and constructed and arranged to continuously charge the screen with a fluid containing separable matter, separate scrapers mounted to rotate about said axis, driving means for said bowl, screen and scrapers constructed and arranged to drive the scrapers at different rates than the bowl and screen respectively, said scrapers being operative to scrape the inside walls of said bowl and said screen whereby the said separable matter is discharged at the bottom of said bowl and said screen, and first and second collectors, each rotatable about an axis common to the axis of rotation of said bowl and said screen for separately collecting the separable matter discharged from said bowl and from said screen.
